UNITED STATES PATENT OFFICE.

HERMAN SAUTER, OF CHICAGO, ILLINOIS, ASSIGNOR TO HERMAN I. NAGER, OF CHICAGO, ILLINOIS.

PAPER-INTERLEAVING MACHINE.

No. 867,159.

Specification of Letters Patent.

Patented Sept. 24, 1907.

Application filed January 10, 1907. Serial No. 381,600.

To all whom it may concern:

Be it known that I, HERMAN SAUTER, a citizen of the United States, residing at Chicago, in the county of Cook and State of Illinois, have invented a certain new and useful Improvement in Paper-Interleaving Machines, of which the following is a specification.

My invention is an automatic machine for interleaving toilet, cigarette, or other paper.

The object of my invention is to provide an automatic machine of this class which will take paper from two continuous strips or rolls of paper, cut off short portions from each strip, crease each cut off portion in its middle, and fold the short pieces coming from each roll together, with the edge of one short piece at the crease of the other short piece, as more fully appears in Figure 16 of the drawings.

My invention consists broadly in a machine capable of accomplishing the foregoing object, which can be comparatively cheaply made, which is efficient in operation, and is not readily liable to get out of order; a novel form of cutting and creasing mechanism; a novel form of folding and pressing mechanism; and in the application of a moving jet or jets of air or other vapor to a folding and pressing mechanism for such machine, 25 to assist in causing the paper to be folded to readily assume its proper position for the operation of the machine.

More in detail, my invention consists in a folding and pressing mechanism so movable with reference to the 30 creasing and cutting mechanism that the paper coming from the creasing and cutting mechanism always enters the folding mechanism in approximately the position which it has to remain in during the operation of the machine.

35 My invention further consists in a novel mechanism for holding the paper taut during the cutting operation, and in novel guiding or switching mechanism for directing the paper through the cutting and creasing mechanism.

40 It also consists in details of construction which will be hereafter more fully described and claimed as the specification proceeds.

Referring now to the drawings in which similar numerals indicate the same parts throughout the several 45 views, Fig. 1 is a front, Fig. 2 a rear, Fig. 3 a side, and Fig. 4 a plan view of a complete machine embodying my invention in its preferred form. Fig. 5 is a sectional view of the machine taken on line 5—5 of Fig. 3. Figs. 6 and 7 are enlarged detail views taken upon line 50 6—6 of Fig. 3, showing two extreme positions of the various parts of the machine there appearing. Fig. 8 is a plan view of the folding and pressing mechanism taken on line 8—8 of Fig. 6. Fig. 9 is a view corresponding to the lower half of Fig. 6, showing the latch member 148 55 and attached parts in withdrawn position, which posi-

tion takes place momentarily after the machine leaves the position of Fig. 7 and is just approaching that of Fig. 6. Fig. 10 is a detail view of a trigger mechanism used in connection with the folding and pressing mechanism. Fig. 11 is a sectional detail view on line 11—11 60 of Fig. 10. Fig. 12 is a perspective detail view of a guide or switch; and Fig. 13 is a similar view of a stripper used in connection with the cutting and creasing mechanism. Fig. 14 is a detail view of a creasing bar or strip, and Fig. 15 is a perspective view of a cutting or 65 perforating strip or bar used in the cutting and perforating mechanism. Fig. 16 is a perspective view of the paper product as it comes from the machine. Fig. 17 is a detail view of mechanism for vertically adjusting the upper cutting and creasing rollers. 70

I provide a suitable table 20 supported on legs 21 upon which my machine rests. Rising from this table and secured thereto by suitable bolts or cap screws 22 are two suitable lower frames 23 and 24. The frames 23 and 24 are, as shown, placed upon opposite sides of a 75 rectangular hole 25 in the table 20. Resting upon the lower frame 23 is a rectangular upper frame 27, and resting upon the lower frame 24 is a corresponding upper frame 28. Each upper frame 27 and 28 has inserted through slots 29 in its lower portion cap screws 30 entering its adjacent lower frame, so that it may be adjusted horizontally with reference to its lower frame under the control of the set screws 31 and 32. Journaled in suitable stationary bearings upon the frame 27 is a 80 shaft 33, carrying a roller 34. Directly opposite this shaft 33 is a corresponding shaft 35 journaled upon the upper frame 28 and carrying a roller 36. Slidably secured upon inner faces of the upper frame 27 and above the roller 34 are plates 39 adapted to move up and down under the control of springs 40 controlled by screws 41, 90 as shown in Fig. 17. These slidable plates 39 are secured to the frame 27 by means of the cap screws 42 passing through vertically elongated slots 45 in the plates 39, the adjustment of the cap screws being such that the plates 39 may be moved up and down with reference to the frame 27 as described. Each of the two plates 39 just described carries on its lower portion a suitable bearing for a shaft 43 on which is mounted an upper roller 44 normally held by the springs 40 in contact with the roller 34 heretofore described. Identical 100 parts consisting of plates 46, cap screws 47, springs 48, adjusting screws 49, shaft 50 and roller 51, are provided upon the upper frame 28. All of the parts just described are so arranged that the roller 51 is held by the spring 48 in contact with the roller 36. The mechanism just 105 described is also so arranged that, for reasons which will readily appear hereafter, the rolls 44 and 51 and the gearing operating them to be hereafter described, do not come in contact with or mesh with each other.

Suitably journaled in the frame of the machine is a 110

main power shaft 55 carrying a suitable wheel 56 or other suitable mechanism through which power may be communicated from an external source thereto. On this shaft 55 is a gear 57 meshing with a gear 58 upon shaft 35. This gear 58 meshes with gear 59 upon the shaft 33, which, in turn, meshes with another gear 60 on the shaft 43. On the shaft 50, heretofore described, is another gear 61, which meshes with the gear 58, but does not mesh with the gear 60. These gears 58, 59, 60, 61 are all the same size, so that when power is communicated to them from the shaft 55, they all rotate at the same speed, and consequently the four shafts 33, 35, 43 and 50, rotate at the same speed, with the result that their corresponding rolls 34, 44, 36 and 51 also rotate at equal speeds. Extending from the upper frame 27 is an arm 63 carrying a shaft 64 on which is journaled an idle flanged guide roller 65. Similarly extending from the upper frame 28 is an arm 66 carrying a shaft 67 and a guide roller 68.

20 Pivoted on suitable bearings 70 upon opposite sides of the upper frame 27 are bell-crank levers 71. The shorter arms of these bell cranks are connected by a rod 72 on which is journaled a roller 73, preferably of rubber or other yielding material. The longer arms of these bell cranks are connected to the upper frame 27 by suitable retractile springs 74, which serve to hold the roller 73 in contact with the roller 34, as is best shown in Fig. 5. Similarly pivoted on suitable bearings 75 upon the upper frame 28, are other bell cranks 30 76. On the shorter arms of these bell cranks is a rod 77 on which is journaled a roller 78 corresponding to the roller 73 heretofore described, said roller being held in contact with the roller 36 by means of the retractile spring 79 corresponding to the spring 74, heretofore described.

In roller 34 I cut four rectangular grooves running the length of the roller, two of them, 81, being empty, as shown, and two of them, 82, being filled with flexible material, such as rubber. In the roller 36 I cut two 40 corresponding empty grooves 83, and two compressible material filled grooves 84. The empty grooves of each roller are staggered with reference to the empty grooves of the adjacent roller, and the filled grooves of each roller are staggered with reference to the filled grooves of the 45 adjacent roller, with the result that a filled groove 82 of the roller 34 will always meet or mesh with an empty groove 83 of the roller 36, as shown in Fig. 6, and a filled groove of roller 36 will always meet or mesh with an empty groove of roller 34, as shown in Fig. 7.

50 In the upper roller 44 adjacent to the roller 34, I mount at intervals 180° apart, two cutting knives 86 adapted to mesh, as shown in Fig. 6, with an empty groove 81 of the roller 34. Midway between these knives 86 upon the roller 44 I place two creasing 55 knives 87 adapted to mesh with the filled grooves in the roller 34, as shown at the left of Fig. 7. Similarly I mount upon the roller 51 other cutting knives 88 adapted, as shown at the left of Fig. 7, to mesh with the open grooves 83 on the roller 36, and intermediate 60 between these I place creasing knives 89 adapted, as shown at the right of Fig. 6, to mesh with the filled grooves of the roller 36.

From the foregoing description of the four rollers, their gearing, and their respective creasing and cutting knives, it will readily be seen that the cutting

knives 86 and 88 upon their respective upper rollers are staggered with reference to each other, and that the creasing knives are correspondingly staggered, with the result that when a continuous strip of paper 91 is fed under the tension rollers 73 and between the 70 rollers 34 and 44, and another strip of paper 92 is fed under the tension rollers 78 and between the rollers 36 and 51, the strip of paper 91 will be cut, as shown in Fig. 6, at the same time the strip of paper 92 is being creased between rollers 36 and 51; that when the paper has moved from the position of Fig. 6 to that of Fig. 7, the paper 92 will be cut while the paper 91 is being creased; and that when the strips of paper are fed downward between the rollers 34 and 36 and cut across the strip, the cut ends of the strip of paper will 80 always meet or mesh with a creased portion of the adjacent strip of paper. Paper is supplied to the machine as best shown in Fig. 5 from suitable rolls located at any convenient points adjacent to the machine; the end of one strip being passed over the 85 roller 65, thence under the roller 73, and thence between the rollers 34 and 44 in the manner described, while the end of the other strip of paper is passed over the roller 68 under the roller 77, and thence between the rollers 36 and 50 in the manner described. 90 After the paper in these two strips 91 and 92 has been cut and creased in the manner described, in passing between their respective sets of vertically disposed rollers, it is necessary to cause them to pass smoothly between the lower pair of rollers 34 and 36, and in 95 order to accomplish this purpose, I provide mechanism which will now be described.

I secure to one of the upper frames 27 or 28, in the particular case here illustrated; the frame 28, a pair of horizontal arms 93 having their outer ends connected 100 by a horizontal rod 94 lying in the vertical central plane of the machine above the centers of the shafts 33 and 35. Upon this rod 94 I secure by set screws 95 a plurality of triangular guides 96 having their lower angular faces 97, 98 curved, so as to conform, as best shown in Figs. 6 and 7, to the surfaces of the rollers 34 and 36, there, however, being sufficient space between the guide and rollers so that the paper strips 91 and 92 may pass, as shown and heretofore described.

In order to be sure that the end of each piece of 110 paper 91 which has been cut off in passing between the rollers 34 and 44 will pass in between the guide 96 and roller 34, as illustrated in Fig. 6, I provide upon the roller 44 adjacent to each cutting knife 86, a horizontal rod or shaft 100, on which, intermediate between the ends of the roller, are rigidly secured a plurality of normally outwardly pointing fingers 101 115 lying in the circumferential grooves 102 in said roller 44. These fingers 101 between the ends of the rollers are normally held outward by springs 103 attached to 120 an end finger 104 at the end of the rod 100, and preferably beyond the end of the roller 44. This end finger 104 has in its outer end a small anti-friction roller 105, best shown in Fig. 5, which is adapted to travel upon a cam 106 located, as shown in Fig. 6, so that as this 125 roller 105 travels over the cam 106 it will, through the agency of its lever 104 and the shaft 100, move the fingers 101 from their outwardly extending position into the position shown in dotted lines at the left of Fig. 6 in which they are wholly within the grooves 130

102, and do not interfere with the roller 44 rotating in contact with the roller 34.

The operation of this part of the mechanism is that, as a cutting knife 86, to which a particular set of fingers 101 is adjacent, reaches the position of Fig. 6, where it cuts a portion of paper 91 from the continuous strip, the fingers 101 are held inside of the circumference of the roller and do not interfere with its operation, but just as soon as the knife 86 passes in a counterclockwise 10 direction slightly beyond the position shown in Fig. 6, the roller 105 is released from the cam 106, which, in turn, releases the ends of the fingers 101 sufficiently so that as the roller 44 rotates, they tend to travel momentarily along the surface of the roller 34 a sufficient 15 distance to hold the cutoff end of the paper 91 in contact with the roller 34 a sufficient length of time to allow said end of paper to pass in under the upper edge of the guide block 96. While this has been taking place, the ends of the fingers 101 have moved out to full-line 20 position, as shown in Fig. 6, in which position they remain until roller 105 again strikes the cam 106. As the machine cuts off two portions of paper from the main roll of paper at each revolution of the roller, I provide one set of fingers 101 for each knife 86 upon the 25 roller 44. Similarly, I provide upon the upper roll 51 a plurality of shafts 108, fingers 109, an end finger 110 carrying a roller 111 adapted to travel upon a cam 112, adapted to cause the foregoing parts to operate with reference to the roller 51 and roller 36, exactly as cam 30 106 caused the mechanism of rollers 34 and 44 to operate.

As heretofore stated, the set screws 41 and 49 and the springs 40 and 48 and their attached mechanism control the pressure of the upper rollers upon the lower rollers, and the pressure between the two lower rollers 35 34 and 36 may be regulated by one or both of the set screws 31.

In order to insure the pieces of cut and creased paper passing in contact with each other from the foregoing mechanism, which will be hereafter referred to as 40 the creasing and cutting mechanism, to the folding and pressing mechanism, I provide below the rollers 34 and 36, and adjacent to the guides 96 a plurality of strippers 114. These strippers 114 are mounted upon supporting rods 115 and their upper ends or points 116 enter grooves 45 117 in the lower rollers, as is best shown in Fig. 6, so that it is impossible for the paper coming from between the lower rollers to cling to the surfaces of said rollers, and the portions of paper must pass downward between the strippers, as is shown in Figs. 6 and 7, to the folding 50 and pressing mechanism, which will now be described.

It is particularly important to be able to adjust the pressure between the rolls 34 and 36, so as to maintain a pull upon the paper strips 91 and 92 to draw them through the cutting and creasing mechanism and to 55 feed them down into the folding mechanism. It is also desirable that tension be maintained here in order to, in combination with the tension exerted by the rolls 73 and 78 heretofore described, stretch the strips of paper 91 and 92 over the lower rolls 34 and 36, as 60 shown, so that when the strips of paper are engaged by the cutting or creasing knives, and particularly the cutting knives, as shown in Figs. 6 and 7, the operation designed to be performed by these knives upon the paper is readily performed.

65 *Cutting and pressing mechanism.*—Rigidly secured in

suitable bearings 120 and 121 is a strong shaft 122, to which is rigidly secured by any suitable means the back 123 of an oscillating box or chute having the side walls 124 and 125. This chute is, as shown, open at the top and bottom, and in the particular machine here 70 illustrated, has no front wall, but one may be provided without departing from my invention. The walls of this chute extend downwardly, as shown in Figs. 2, 3 and 5, a considerable distance. This chute may have a slideable stop or holder, in frictional contact with the 75 sides of the chute, adapted to resist the passage of the product of the machine a sufficient amount to maintain the pile or column of product in proper form in the chute, but, in practice, I find that after a few inches of the folded paper product has started down the chute, 80 the friction of the product upon the walls of the chute is sufficient to maintain the column of product in proper form without such a device. In order to oscillate the shaft 122, and consequently the chute, just described, I rigidly secure to said shaft 122 by any suitable means, 85 an upwardly extending crank-arm 127 having in its upper end a slot 128 in which a bolt 129 is adapted to be secured in different positions. Journaled upon this bolt 129 is a short connecting rod 130, having its other end journaled upon a crank pin at the end of a 90 crank arm 132. This crank arm 132 is mounted upon a shaft 133 which carries a pinion 134 meshing with a gear 135, which is twice its size, mounted upon the shaft of one of the rollers heretofore described. The reason for this proportioning of the gears 134 and 135 95 is that, as will hereafter appear, the chute must make two oscillations in order to take care of the two small pieces of paper coming from each lower roller 34 and 36 during their complete revolution. If these lower rollers were designed to only produce one small 100 piece of paper per revolution of each roller, gears 134 and 135 should be of the same size. The oscillating mechanism just described is so proportioned that the chute first assumes the position of Fig. 6 when the middle of one piece of product paper and the end of 105 another piece of the same have come from the cutting and creasing mechanism to a point adjacent to one edge of the chute, and are ready to be folded; and that as said pieces are folded the chute moves from the position of said Fig. 6 to that of Fig. 7, in which the next succeeding portion of paper coming from the machine is in such a position that, as shown, its creased portion and cut ends are adjacent to the opposite side of the chute 110 and is ready to be folded.

On the outside of the wall 125 of the chute heretofore described, I journal a shaft 138 carrying one or more upwardly extending lever arms 139 on the upper ends of which are cap screws 140. Loosely mounted upon the upper ends of this lever arm 139, under said cap screws, in such a manner that they may be moved 120 slightly up and down in a vertical plane, are one or more horizontal, pointed latch members 141, extending as best shown in Fig. 9, through a suitable slot or slots 142 in the wall 125. These latch members 141 are yieldingly held in position with their pointed ends 125 elevated by means of a retractile spring or springs 143. Similarly, I provide adjacent to the wall 124 of the chute a shaft 145, lever arms 146 carrying cap screws 147, under which are mounted latch members 148 adapted to pass through slots 149 in the wall 124, 130

and to be controlled by the springs 150 corresponding to springs 143, heretofore described.

Rigidly secured upon the shaft 138 by means of a suitable set screw 152, is a short lever arm 153. Pivotedly mounted at 154 in this arm is a latch 155 normally pressed outward by means of a spring 156, the motion of the latch being limited by the short arm 157 acting against lever arm proper 153, as is best shown in Fig. 11. This lever arm and its connected mechanism just described, is, as is best shown in Fig. 8, in the same vertical plane with a lever 159 loosely journaled upon the shaft 145. On the shorter end of this lever 159 is an inclined angular face 160 bearing against the face of the latch 155, heretofore described. The longer end 15 of the lever 159 is adjustably controlled and limited in motion by the adjustable stops 161 and 162. Similarly mounted upon the shaft 145, there is another short lever arm 163 corresponding to lever arm 153, having a latch 165 corresponding to latch 155. Opposite this lever arm 163 and latch 165 there is journaled upon the shaft 138 a lever 169 having an angular face 170 adapted to bear against the face of the latch 165 exactly in the same way that the face 160 of the lever 159 bears upon the face of the latch 155. This lever 169 is limited and controlled by adjustable stops 167 and 168 corresponding to the stops 161 and 162, heretofore described.

The parts just described are normally held in the position of Fig. 6 by means of a spring 171 connected at the upper end to a stationary arm 172 extending from the wall 124, and at the other end to the shaft 145. Similarly, the shaft 138 is connected to a spring 173 which has its other end connected to an arm 174 extending from the wall 125. This spring serves to hold the latch 141 and attached mechanism normally in the 30 position of Fig. 9.

Assuming now that the parts just described are in the position of Fig. 7 the spring (not shown) corresponding to spring 156 throws the latch 165 outward to the position of Fig. 7, in which position it is in the 40 way of the extreme point of the face 170 of the lever 169. When, now, the oscillation of the shaft 122 starts to rock the chute from the position of Fig. 7 to that of Fig. 6, the point of the face 170 is engaged by the lower corner of the latch 165. The first result of this 45 is to move the lever 169 upward to the position of Fig. 9, in which position its longer end 169 is stopped by the stop 167. As the latch 165 still engages the point of the face 170 of this lever, it follows that the lever 163 must move the lever-arm 146 toward the position 50 of Fig. 9. When this position is reached and slightly passed, the point of the latch 165 clicks off from the point of the face 170 of the lever 169, and the lever 146 immediately swings back under the action of spring 171 to the position of Fig. 6, with the result 55 that the latch 148 is quickly slipped, as shown in Fig. 6, over the paper which has just been folded, and holds it down, so that the folding or pressing lever 176, which will be hereafter described, may be removed. The lever and latch mechanism controlling 60 the latch 141, operates in exactly the same manner as the mechanism just described, except that it operates just as the mechanism reaches the position of Fig. 7.

Pivoted to the arm or arms 172, heretofore described, is a suitable shaft 177 on which are a plurality of short 65 lever arms 176 adapted to enter the wall 124, hereto-

fore described, through suitable slots open at their tops, and travel downward from the position of Fig. 7 to that of Fig. 6, to press down the paper within the chute.

Adjustably secured to the shaft 177 which carries 70 these levers 176, by means of a set screw 178, as is best shown in Fig. 8, is a longer lever 179, having its end 180 adapted to travel backward and forward upon the top of the table 20, said table performing the functions of a cam to move the lever 179 and the attached 75 levers 176, from the position of Fig. 7 to that of Fig. 6 and back again, as the chute makes a complete oscillation, as heretofore described. Similarly I mount upon a suitable shaft or bearing 182 carried by one or more arms 174, a plurality of short, presser lever arms 80 183, adapted to enter the wall 125 of the chute, and press down the paper therein, as shown in Fig. 7, said lever arms 183 being connected by suitable set screw mechanism corresponding to set screw 178 to a lever 184, having its end 185 adapted to travel on the table 85 80 exactly as the end 180 of the lever 179 does, and for the same purpose.

In the complete operation of the folding and pressing mechanism, as thus far described, the cutting and creasing mechanism feeds down properly creased and 90 cut paper, as heretofore described, into the chute in the position of Fig. 6, with the two adjacent cut ends of one strip of paper adjacent to the crease of the other strip of paper, and all in the corner over the latch 141 and adjacent to the wall 125, as shown in Fig. 6. As 95 the chute now begins to oscillate toward the position of Fig. 7, the short lever arms 183 are moved to the position of Fig. 7. As soon as this occurs, the latches 141 are withdrawn as described, and snapped in again over the freshly folded paper and below a plate 186, 100 which covers the lower face of the lever arms 183. While this operation has been going on, more paper has been fed down, so that the next adjacent crease and adjacent cut edges of the combined strips of paper are in the corner over the latch 148, and adjacent to the wall 124, as shown in Fig. 7. The chute now starts to oscillate in the opposite direction, with the result that the plate 187 on the lower face of the lever arms 176 travels along the incoming paper, and presses it down to the position of Fig. 6, after which the latches 110 148 are withdrawn and snapped in again as heretofore described.

In attempting to operate the machine at a high rate of speed, and secure the operation just described, I have found great difficulty with only the mechanism 115 just described, in causing the paper to reach the desired corners described, so that accurate folding may take place. I therefore provide an air blast mechanism which supplies, at the proper instant, a blast of air or other gas to blow the paper into proper position. 120 This mechanism will now be described. In order to accomplish this object, I journal in suitable bearings 188 and 189 formed in the opposite side frames, two horizontal pipes 190 and 191 best shown in Fig. 8. The ends of these pipes are so mounted that they form 125 bearings about which these pipes and mechanisms attached thereto may oscillate or rock in a vertical plane within reasonable limits. Extending from the pipe 190 are two small blast pipes 192 and 193 having their ends or nozzles 194 and 195 turned inward. These ends 194, 130

195 are so located and the curvature of their ends is such, that, as shown in Figs. 7 and 8, air issuing from them will strike the creased and cut paper coming into the folding mechanism, in such a position that the 5 blasts of air tend to force the paper into the position of Fig. 7. This is accomplished quite largely by reason of the fact that the inwardly turned jets strike the opposite outer edges of the paper to be folded, at an angle and the air after leaving the nozzles travels outward 10 toward the opposite edges of the paper. Similarly, from the pipe 191 I provide other blast pipes 196 and 197 having inwardly turned ends 198 and 199, so located that, as shown in Fig. 6, they strike the paper when it is in the position of that figure just ready to be 15 folded. Journaled in suitable bearings upon the upper frame of the machine, and outside of the bearings for the pipes 190 and 191, I mount two shafts 200 and 201, carrying eccentrics 202 and 203, in which rest the supply pipes 204 and 205 for the pipes 190 and 191, respectively. On these shafts 200 and 201 are mounted 20 sprocket pinions 206 and 207, connected by sprocket chains 208 and 209 with sprocket gears 210 and 211, mounted respectively upon the shafts of the upper rolls of the cutting and creasing mechanism, as is best shown 25 in Fig. 2. These eccentrics 202 and 203 are so located upon their respective shafts, that as the upper rollers of the cutting and creasing mechanism revolve, these eccentrics cause the pipes 204 and 205 to move up and down in a vertical plane a sufficient distance so that 30 the ends 192 and 193 and 198 and 199 of the various blast pipes follow the paper which is being folded in adjacent to them, and cause the air escaping from them to strike the paper at just the right position as it is folded in, and follow it downward a sufficient length of 35 time to allow it to be folded.

The outer end of the pipe 205 is connected by means of a flexible pipe 213 with the casing 214 of an air supply valve, having extending from its upper end a valve rod 215 adapted to be moved up and down to control 40 the passage of air from a main supply pipe 216 through the casing 214 to the pipe 213. Similarly, the pipe 204 is connected by a flexible pipe 217 to a valve casing 218, containing a rod 219 controlling the passage of air from the pipe 220 to the pipe 217. The pipes 216 and 45 220 are connected by a pipe 221 to any convenient source of compressed air. Rigidly secured to the shaft 122, heretofore described, is a vertically extending lever arm 222, carrying upon its upper end horizontal arms 223 and 224; the arm 223 being adapted to engage the valve stem 215, and the arm 224 being adapted to engage the valve stem 219, heretofore described. These rods 223 and 224 have a slotted connection with the lever arm 222, by means of the slots 225, and bolt 226, so that they may be adjusted to this vertical position 50 upon the arm 222. They are also so shaped that only one of them touches its adjacent valve stem at a time. The entire mechanism is so proportioned with reference to the other parts of the machine, that the lever arm 123 will operate the valve stem 215 at the 55 proper time to admit air through the nozzle ends 194 and 195, when it is desired that air shall be so admitted for the purpose of assisting the folding operation on one side of the machine, as heretofore described, and that the lever arm 224 will operate the valve 219 at the 60 proper time to admit air through the nozzle ends 198

and 199 to cause them to assist in the following operation at the opposite side of the machine, as heretofore described.

While the machine as thus far described does very satisfactory work, I find that still more efficient action 70 can be obtained by introducing into the machine a steam pipe 228, having its supply through a pipe 229. The ends 230 and 231 are so located that they are under a paper approaching the machine over large rollers 68 and 65, respectively. When, now, a moderate quantity of steam or other similar moist gas is allowed to escape from the ends of these pipes under the paper passing over these rollers, it will moisten the same sufficiently to take out any excessive stiffness, and render the operation of the machine upon the paper more easy 80 and satisfactory. 75 80

It will be noticed that the width of paper operated upon by the machine has not been specified, and the same forms no portion of my invention. By making the cutting and creasing rollers of sufficient width and 85 the chute of corresponding dimensions, and correspondingly increasing the number of folding fingers extending crosswise of the machine, almost any desired width of paper may be operated upon by the device of my invention. 90

While I have described the cutting knives 86 and 88 as wholly severing the strips of paper 91 and 92 on which they act it is manifest that only a perforation for severance of the paper may be made without departing 95 from my invention.

It will be noticed that each original strip of paper 91 and 92 is, irrespective of its being cut up into short pieces, ultimately folded in zigzag form into the chute. For convenience this term will be used in some of the 100 claims.

What I claim as new and desire to secure by Letters Patent, is:

1. A machine comprising a cutting and creasing mechanism, adapted to deliver two strips of paper, cut and creased as described, and an oscillating chute adjacent to the point of delivery of the aforesaid paper, provided with folding mechanism adapted to fold said paper into an interleaved pile within the chute. 105

2. A machine comprising a cutting and creasing mechanism, adapted to deliver two strips of paper cut and creased as described, and a moving chute, adjacent to the point of delivery of the aforesaid paper, provided with folding mechanism adapted to fold said paper into an interleaved pile within the chute. 110

3. A machine including, mechanism for feeding out cut and creased pieces of paper as described; a chute so located as to receive the paper from the cutting and creasing mechanism movable transversely with reference to the line of travel of the paper from the cutting and creasing mechanism, provided with folding mechanism for folding 115 said paper in zigzag form within the chute and mechanism for causing all of said parts to operate together for the purposes set forth.

4. A machine comprising means for cutting off and creasing two adjacent strips of paper and adapted to deliver the same with the adjacent cut ends of portions of one strip of paper adjacent to the lines of crease in the cut off portions of the second strip of paper as described; a chute provided with folding mechanism adapted to fold said paper in opposite directions along the successive 120 creases to form an interleaved pile as described and mechanism for moving said chute to different positions so that when a fold is about to be made in said paper it is entering the chute adjacent to the folding mechanism which is next to operate upon it. 125

5. The combination of mechanism adapted to fold a 130

strip of paper, means adjacent to said folding mechanism adapted to temporarily direct a blast of air against paper about to be folded to force it into engagement with the folding mechanism and means for varying the direction 5 of said blast of air during the folding operation.

6. The combination of mechanism adapted to fold a strip of paper and means adjacent to said folding mechanism adapted to temporarily direct blasts of air against opposite side portions of the paper about to be folded to 10 force it into engagement with the folding mechanism, and means for causing said blasts of air to travel along the edges of said paper as it is engaged by the folding mechanism.

7. The combination of mechanism adapted to fold a strip of paper and means adjacent to said folding mechanism adapted to temporarily direct blasts of air against opposite side portions of the paper about to be folded in 15 directions angular to the edges of the paper to force it into engagement with the folding mechanism and means for causing said blasts of air to travel along the edges of 20 said paper as it is engaged by the folding mechanism.

8. In mechanism of the class described the combination of mechanism adapted to fold a strip of paper, an air pipe having a nozzle and directed toward the position assumed by paper about to be folded by the folding mechanism and its other end connected to a valve for controlling the admission of compressed air to said pipe, a pivotal mounting for said pipe, a cam adapted to move said pipe upon said pivotal bearing and mechanism adapted to so 25 operate said valve, the cam and said folding mechanism that the air temporarily emerges from said pipe, and follows paper about to be folded to force it into the folding mechanism.

9. In mechanism of the class described two rolls bearing 30 against each other, two cutting rolls clearing each other each bearing against one of the first rolls, one or more cutting knives, and a corresponding number of creasing knives on each cutting roll meshing with suitable grooves in the adjacent first roll, said knives of each 35 class in each roll being staggered with reference to those of the same class on the other roll for the purposes set forth.

10. In a machine of the class described, two rolls bearing against each other, two cutting rolls clearing each 40 other each bearing against one of the first rolls, one or more cutting knives and a corresponding number of creasing knives on each cutting roll meshing with suitable grooves in the adjacent first roll, said knives of each class 45 on each roll being staggered with reference to those of the same class on the other roll, and means for directing an end of a piece of paper coming from between each cutting roll and its adjacent first roll so that it then passes between the first rolls.

11. In machine of the class described, two rolls bearing 50 against each other, two cutting rolls clearing each other each bearing against one of the first rolls, means for directing the end of a sheet of paper which has come from between each cutting roll and its adjacent first roll so that it then passes between the first rolls, means for supplying a strip of paper to each cutting roll and its first 55 roll so that it passes between them into said directing means, means for placing tension on each strip of paper as it approaches its cutting and first roll, one or more cutting knives and a corresponding number of creasing 60 knives on each cutting roll meshing with suitable grooves in the adjacent first roll at the point of contact of each cutting roll with its adjacent first roll whereby the paper passing between said first rolls is cut or creased as desired and then passes between the first rolls for the purposes described.

12. In a machine of the class described, two rolls bearing 65 against each other, two cutting rolls clearing each other each bearing against one of the first rolls, means for directing the end of a sheet of paper which has come from between each cutting roll and its adjacent first roll so that it then passes between the first rolls, means for supplying a strip of paper to each cutting roll and its first 70 roll so that it passes into said directing means, means for placing tension on each strip of paper as it approaches its cutting and first rolls, one or more cutting knives and

a corresponding number of creasing knives on each cutting roll meshing with suitable grooves in the adjacent first roll at the point of contact of each cutting roll with its adjacent first roll whereby the paper passing between said first rolls is cut or creased as desired and then passes 85 between the first rolls, and means for stripping both strips of paper from the first rolls for the purposes described.

13. In mechanism of the class described in combination with mechanism for providing a continuous supply of paper, a chute into which said paper passes, means for oscillating said chute so that the paper going into it is alternately adjacent to opposite walls of the chute, temporary supporting prongs projecting inside the walls of the chute adjacent to the lines of fold of the paper and folding fingers mounted upon each wall of the chute adjacent to the 90 supporting prongs adapted to, as said chute oscillates, fold said paper in zigzag form within the chute with successive folds upon the prongs on opposite sides of the chute for the purposes described.

14. In mechanism of the class described in combination 100 with mechanism for providing a continuous supply of paper, a chute into which said paper passes, means for oscillating said chute between two different positions in which opposite walls of the chute are adjacent to the path of the paper going into the chute, mechanism adapted to 105 fold paper going into the chute in zigzag form as described, movable supports adjacent to the points in the chute walls, in which the folding fingers form the folds upon the paper, capable of supporting the paper while the folding fingers make the folds, also capable of being sprung outside of the 110 chute so as to let the folded paper pass them and then spring back into the chute to hold down the folded paper and mechanism for normally so moving the various members of the combination for the purposes described.

15. In a machine of the class described, the combination 115 of a suitable base frame, two other frames rising therefrom, four rolls journaled therein, two of said rolls bearing against each other, and one of each of the other or cutting rolls bearing against a first roll but not against the other first roll; gearing for rotating all of said rolls at the 120 same speed, one or more cutting and an equal number of creasing knives on each cutting roll meshing with suitable grooves in the adjacent first roll, the knives of the same class on each roll being staggered with reference to knives of the same class on the other roll; means for supplying 125 strips of paper, from the outside of the machine, between each first roll and its adjacent cutting roll toward the center of the machine, means for maintaining tension on the paper while being cut, means for causing the cut ends of paper to, after being cut follow the adjacent first roll 130 in between the first rolls, means for stripping the paper off from the first rolls as it comes from between the first rolls; a chute pivotally mounted on the frame with its upper end adjacent to the point of delivery of the paper from the first rolls, means for oscillating the chute between two positions in which the paper is alternately adjacent to opposite walls of the chute, folding mechanism on each of said walls of the chute adapted to fold the paper when then adjacent to it along a line of crease on one strip of paper and a line of cut on the other strip of paper 140 previously made by the cutting and creasing mechanism, means for temporarily supporting the paper in the chute, during the folding operation, means for temporarily directing a blast of air against the paper adjacent to a folding mechanism to force it into engagement with the folding mechanism and means for causing all of said parts to operate in proper order for the purposes set forth.

16. In a machine of the class described, a support, a chute for paper pivotally mounted thereon, means for supplying paper to the open end of the chute, means for oscillating said chute between two different positions in each of which the paper is adjacent to an opposite wall of the chute, levers, pivotally mounted on bearings carried by the chute adjacent to each of said side walls each having a finger adapted to fold down paper adjacent to its side wall, means for so guiding said levers that as the chute oscillates the fingers successively so fold down portions of the paper then adjacent to the wall on which the particular finger is mounted, and mechanism for temporarily supporting the paper during each folding operation. 155

17. In a machine of the class described, a support, a chute for paper pivotally mounted thereon, means for supplying paper to the open end of the chute, means for oscillating said chute between two different positions in each of which the paper is adjacent to an opposite wall of the chute, levers, pivotally mounted on bearings carried by the chute adjacent to each of said side walls each having a finger adapted to fold down paper adjacent to its side wall, means for so guiding said levers that as the chute oscillates the fingers successively so fold down portions of the paper then adjacent to the wall on which the particular finger is mounted, and mechanism for temporarily supporting the paper during each folding operation. 160

17. In a machine of the class described, a support, a chute for paper pivotally mounted thereon, means for supplying paper to the open end of the chute, means for oscillating said chute between two different positions in each of which the paper is adjacent to an opposite wall of the chute, levers, pivotally mounted on bearings carried by the chute adjacent to each of said side walls each having a finger adapted to fold down paper adjacent to its side wall, means for so guiding said levers that as the chute 10 oscillates the fingers successively so fold down portions of the paper then adjacent to the wall on which the particular finger is mounted, mechanism for temporarily supporting the paper during each folding operation and mechanism adapted to temporarily withdraw said supporting mechanism as a particular fold is completed and reinsert it above the fold for the purposes set forth.
18. In a machine of the class described, a support, a chute for paper pivotally mounted thereon, means for supplying paper to the open end of the chute, means for oscillating said chute between two different positions in each of which the paper is adjacent to an opposite wall of the chute, levers pivotally mounted adjacent to each of said opposite walls of the chute, supporting latch members mounted on said levers extending inside the adjacent wall 20 of the chute, spring mechanism for normally holding said latch members in said positions, a mechanism adapted to move said levers to successively withdraw said latch members from the chute against the action of said spring mechanism and mechanism for quickly disengaging said withdrawing mechanism so that each of said latch members is quickly reinserted in the chute at the proper times for the purposes set forth.
19. In a machine of the class described a support, a chute for paper pivotally mounted thereon, means for supplying paper to the open end of the chute, means for oscillating said chute between two different positions in each of which the paper is adjacent to an opposite wall of the chute, levers pivotally mounted one adjacent to each wall of the chute, having a finger adapted to fold down paper 25 within the chute adjacent to its side wall, means for so guiding said levers that as the chute oscillates the finger successively folds down portions of the paper then adjacent to the wall on which the said finger is mounted, other levers 139 and 146 pivotally mounted adjacent to opposite sides of the chute, each carrying a latch member 141 and 148 entering an opposite side wall of the chute adjacent to the folding position of one of said folding fingers, short lever arms 153 and 163 secured to said levers 139 and 146, a latch 155 pivotally mounted upon the lever 153, a latch 50 165 pivotally mounted upon the lever 163, a supplemental lever 159 pivotally mounted upon the axis of the lever 146 having an angular face 160 engaging the latch 155, means for regulating the arc of travel of said lever 159 another supplemental lever 169 pivotally mounted upon the pivotal bearing of the lever 139 having an angular face 170 adapted to bear against the latch 165, means for regulating the arc of travel of lever 169 and spring mechanism normally holding said levers 139 and 146 in normal 55 position with the latches 141 and 148 extending inside the chute the whole so arranged that when paper is fed 60 into the chute and it is oscillated said paper is folded in zigzag form as described.
20. A machine comprising, a cutting and creasing mechanism, adapted to deliver two strips of paper cut and creased as described, a chute adjacent to the point of delivery of the aforesaid paper, provided with folding mechanism adapted to fold said paper into an interleaved pile within the chute and means for varying the place of entry of the paper into the chute by changing the relative positions of, the cutting and creasing mechanism, and the chute, with reference to each other, between the making of successive folds in the paper.
21. A machine including, mechanism for feeding out cut and creased pieces of paper as described, a chute so located as to receive the paper from said cutting and creasing mechanism movable transversely with reference to the line of travel of the paper from the cutting and creasing mechanism, said chute being provided with folding mechanism for folding said paper in zigzag form within the chute, one or more nozzles carried by the supports which carry the cutting and creasing mechanism adapted to deliver a blast or blasts of air against the paper to force it into engagement with the folding mechanism as it is about to be operated upon by said folding mechanism and means for causing all the said parts to operate together for the purposes set forth.
22. A machine comprising, a cutting and creasing mechanism, adapted to deliver two strips of paper cut and creased as described, a chute adjacent to the point of delivery of the aforesaid paper, provided with folding mechanism adapted to fold said paper into an interleaved pile within the chute, means for varying the place of entry of the paper into the chute by changing the relative positions of the cutting and creasing mechanism and the chute with reference to each other between the making of successive 80 folds in the paper, and one or more nozzles, carried by the same supports as the cutting and creasing mechanism, adapted to deliver a blast or blasts of air against the paper to force it into engagement with the folding mechanism as it is about to be operated upon by said folding mechanism.
23. The combination of a stationary support carrying mechanism for feeding out cut and creased pieces of paper as described, mechanism adapted to fold a strip of paper coming from the cutting and creasing mechanism, means 90 for moving said folding mechanism between two different positions with reference to the cutting and creasing mechanism and means carried by the support for the cutting and creasing mechanism for delivering temporary blasts of air against the paper to force it into engagement with the 95 folding mechanism.
- In witness whereof, I have hereunto subscribed my name in the presence of two witnesses.
- HERMAN SAUTER.
